UNITED STATES PATENT OFFICE

THOMAS H. DENISON, OF BALTIMORE, MARYLAND.

DESIGN FOR A CAMPAIGN-BADGE.

Specification forming part of Design No. 6,096, dated September 3, 1872.

To all whom it may concern:

Be it known that I, THOMAS H. DENISON, of the city and county of Baltimore and State of Maryland, have invented a new Design, of which the following is a full, clear, and exact description, reference being had to the accompanying drawing making part of this specification, in which—

Figure 1 is a front view. Fig. 2 is a side view.

A New Campaign-Badge.

The nature of my invention consists in giving to the badge such an outline as will represent the head of Horace Greeley with a hat upon the same, while the front of the badge shall have printed thereon his likeness, all as clearly represented in Fig. 1. Mr. Greeley's white beard is represented by floss inserted and secured between the layers of the paste or card board on which the design is printed. In Fig. 2 is clearly represented the means of

attaching the badge to the coat, dress, or other garment; and consists simply of a pin bent in the form of a hook inserted between the layers of the card or other material on which the design is printed; or, if desired, instead of being printed, the badge may be stamped or cut out of metal or any other suitable material.

What I claim as new, and desire to secure by Letters Patent of the United States, is—

The design for a campaign-badge, consisting of the likeness of Horace Greeley, as represented in Fig. 1 of the accompanying drawing.

In testimony whereof I have signed my name to this specification in the presence of two subscribing witnesses.

T. H. DENISON.

Witnesses:

EDWIN JAMES,
JOS. T. K. PLANT.
